CLAIM

The ornamental design for a vehicular wheel arch, as shown and described.

DESCRIPTION

FIG. 1 is a front perspective view of a vehicular wheel arch, of the new design;

FIG. 2 is a rear perspective view thereof;

FIG. 3 is a side view thereof;

FIG. 4 is a back side view thereof;

FIG. 5 is a top view thereof;

FIG. 6 is a bottom view thereof;

FIG. 7 is a front view thereof; and,

FIG. 8 is a rear view thereof.

The broken lines in the drawings illustrate portions of the vehicular wheel arch that form no part of the claimed design.
